CORRUGATED PAPER

Paul Brown, Walpole, N. H., assignor to Packaging Materials Corp., a corporation of Rhode Island

Application March 30, 1951, Serial No. 218,314

4 Claims. (Cl. 154—55)

1

This invention relates to packaging material such as used for the packaging of glassware and other frangible objects, and is specifically an improvement on the packaging material disclosed in the patent to E. L. Perry, No. 2,209,537.

Frangible articles packed with the packaging material described and claimed in the above mentioned patent are much less subject to breakage than when packed with straw and excelsior in the usual manner, and with the new material forming the subject-matter of this application the breakage is still further reduced, so that the loss from damage in transit of fragile glassware wrapped therein is almost negligible.

In the accompanying drawings I have illustrated my improved packing material in the form of a flat sheet and also in certain modified forms, and in the said drawings.

Figure 1 is a perspective showing my improved packing material in flat form;

Fig. 2 is a sectional view on an enlarged scale of a portion of an article wrapped with my improved material;

Fig. 3 is a view similar to Fig. 1 showing a modified form of my improved material; and

Fig. 4 is a sectional view showing the method of making a second modified form of my invention.

Referring to the drawings, 1 indicates a sheet of molded corrugated paper similar to that disclosed in the Perry patent above mentioned but without the backing sheet, therein described. This sheet is formed by molding the pulp directly into a corrugated sheet in accordance with the procedure described in Patent No. 2,221,200 also issued to E. L. Perry.

The molded corrugated sheet is preferably of the form shown in Fig. 1, consisting, as there shown, of ribs or corrugations 2 of molded pulp connected by intermediate portions 3 also of molded pulp, which are soft and flexible and substantially thinner than the corrugated portions. The back of the sheet, as shown, is not smooth, but presents a rough air-dried finish with shallow grooves 3a underlying the corrugations 2.

A thin sheet 4 of flexible paper is cemented across the crowns of the corrugations 2. Any suitable cement which does not significantly harden or stiffen the paper may be used. A casein glue such as widely used in the manufacture of coated paper is satisfactory. The sheet 4 is thin relatively to the thickness of ribs 2, and flexible, but not extensible, and consequently when the packing sheet is wrapped around a fragile article,

as shown in Fig. 2, the inner, or intermediate, portions 3 of the corrugated sheet between the corrugations 2 are bowed outwardly as shown at 5 to thereby form the contacting portions of the sheet with the enclosed article.

By the construction shown the article is protected against breakage to an extent not obtainable with any other form of packing material. Breakage of fragile articles results primarily from the impact of one article against another in the container if the container is dropped from an excessive elevation, and from the force of an external blow if transmitted to the article adjacent the wall of the carton at the point struck. With my improved packing material the surfaces of the articles are in contact only with the crowns of the curved thin portions 3 of the corrugated sheet which are maintained in convex form by the thin backing sheet 4.

Thin frangible articles of glassware such as light bulbs, wine goblets and the like, are usually light in weight and have little inertia. Consequently when a package of articles packed with my improved packing sheet is dropped from an undue height the impact of dropping is readily absorbed by the portions 3 of the corrugated packing sheet which are soft and yield readily under pressure of an article of light weight. The convex portions 3 of the corrugated sheet thus permit a sufficient movement of the articles to absorb their momentum when the movement of the carton is suddenly stopped by contacting an unyielding surface. The molded ribs forming the corrugations are also quite soft and yielding, as pointed out in the above Perry patent, and will continue to absorb the shock of impact should there be any movement of the articles after the cushioning effect of the intermediate part 3 is exhausted.

My improved packaging material also protects the article from breakage from an outside blow to a greater extent than the material described in the above mentioned patent. A thin, frangible article will be crushed from the impact of an outside force if concentrated on a small area of the surface of the article but will not be crushed if the same force is distributed over a substantially larger area. Hence if any fairly thin portions of the packing material which are in direct contact with the article are also in contact with the wall of the carton at the point of impact the article may be broken even though the carton is undamaged. No such areas are present in my improved packing material, and unless the pressure on the carton or the force

of the blow received by the carton is sufficient to deform or rupture the carton the contents will not be damaged.

The ribs 2 of my packing material are adjacent the walls of the carton or packing case in which the articles are packed and the force of a blow on the outside of the carton must be transmitted through the ribs 2 and intermediate portions 3 before reaching the article.

To increase the flexibility of the packaging material in a direction transverse to the ribs forming the corrugations I may, before applying the backing sheet 4 to the molded corrugated board, score the corrugated face of the board 2 with a series of parallel score lines extending transversely of the ribs 2 forming the corrugations as shown at 6 in Fig. 3. The score lines may be formed in the board on the board-making machine in the manner illustrated in the copending application of Eugene L. Perry, Ser. No. 100,702, filed June 22, 1949, or the score lines may be formed in the finished board by running the corrugated sheets through scoring rollers having the scoring knives spaced the desired distance apart.

The presence of the score lines does not lessen the protection afforded by the packing sheet when wrapped around a frangible article, but serves merely to facilitate folding in the ends of the sheet along lines transverse to the ribs 2.

Instead of making the packing material in the form of a flat sheet as illustrated in Fig. 1, it may be conveniently manufactured as shown in Fig. 4, with the backing sheet 4 shorter than the base of the sheet. As here shown, instead of gluing the backing sheet to the corrugated sheet when the latter is supported on a flat surface, the gluing is effected by pressing the corrugated sheet, to which adhesive has been applied along the crowns of the corrugation, against the backing sheet while the latter is passing over a backing roller, a portion of which is indicated at 1. This method of manufacture can be readily carried out by a continuously operating machine, as will be obvious, and the web so formed wound into a roll with the backing sheet on the side toward the axis of the roll.

When the sheet is formed in this manner the intermediate portions 3 will be bulged away from the backing sheet 4 even when the sheet is wrapped around a flat-sided article, thereby producing an even greater cushioning effect than when the sheet is formed in the manner shown in Fig. 1.

I claim:

1. Packaging material comprising a molded sheet having spaced corrugations connected by

intervening, flexible portions, the material in said corrugations being substantially thicker than the material in said intervening portions, and a sheet of flexible, non-extensible material attached to the crowns of the corrugations, said sheet being relatively thin in comparison to the thickness of the corrugations.

2. Packaging material comprising a molded sheet having spaced corrugations, shallow grooves underlying said corrugations, said corrugations being connected by intervening, flexible portions, the material in said corrugations being substantially thicker than the material in said intervening portions, and a sheet of flexible, non-extensible material attached to the crowns of the corrugations, said sheet being relatively thin in comparison to the thickness of the corrugations.

3. Packaging material comprising a molded sheet having spaced corrugations connected by intervening flexible portions, the material in said corrugations being substantially thicker than the material in said intervening portions, the face of the corrugations having spaced scorings extending to a depth less than the height of the corrugations above the intervening portions, and a sheet of flexible, non-extensible material attached to the crowns of the scored corrugations, said sheet being relatively thin in comparison to the thickness of said corrugations.

4. Packaging material comprising a molded sheet having spaced corrugations connected by intervening flexible portions, the material in said corrugations being substantially thicker than the material in said intervening portions, and a sheet of flexible, non-extensible material attached to the crowns of the corrugations, said sheet being relatively thin in comparison to the thickness of the corrugations and the length of said sheet between its lines of attachment to said corrugations being shorter than the distance between said corrugations along the opposite surface of the corrugated sheet.

PAUL BROWN.
